UNITED STATES PATENT OFFICE.

EDWARD C. DELSING, OF CHICAGO, ILLINOIS, ASSIGNOR, BY MESNE ASSIGNMENTS, TO KWIK-KUT KNIFE CO., OF ST. LOUIS, MISSOURI, A CORPORATION OF MISSOURI.

KNIFE.

Application filed November 22, 1919, Serial No. 339,896. Renewed October 12, 1922. Serial No. 594,202.

To all whom it may concern:

Be it known that I, EDWARD C. DELSING, a citizen of the United States, residing at Chicago, in the county of Cook and State of Illinois, have invented certain new and useful Improvements in Knives, of which the following is a specification.

This invention relates to knives of the kind in which the blade may fold into its handle, thus adapting the instrument to be carried around in the pocket, and in particular it is concerned with a novel construction by which the blade is removably secured in place.

15 A suggestive embodiment of this invention is shown in the accompanying drawing wherein:

Figure 1 is a perspective view of the knife opened out;

20 Fig. 2 is a similar view showing the knife closed up;

Fig. 3 is a section taken transversely of Fig. 2;

25 Fig. 4 is a fragmentary detail showing the construction at the hinged end of the handle; and

Fig. 5 is a detail in perspective of the outer end of the blade carrier.

The present knife comprises three distinct 30 parts—a blade 6 secured within a carrier 7 which is pivoted to a handle 8. As shown, the blade may be of the usual kind that is used in a safety razor, but, if preferred, may be formed differently so long as will answer 35 the requirements of this invention.

The handle, in the form shown, may be 40 made of sheet metal, which is bent in channel formation with its edges 9 preferably bent upon itself (see Fig. 3), a clearance being provided between these edges for the reception of the blade 6. At one end the handle terminates in an eye portion 10 having at one point a notch or indentation 11 formed adjacent its outer edge. At the other end of 45 the handle, best illustrated in Fig. 4, the outer walls terminate short of its bent over inner walls so as to provide shoulders 12, and the inner walls which extend therebeyond terminate in ears 13 having apertures 50 14 through which a hinge pin 15 may extend to connect with the blade carrier 7.

The carrier which may also be made of sheet metal is shown to be of channel formation with side walls 16 which are inturned at 55 its edges as at 17 to provide a guideway

within which the blade may be received. As best shown in Fig. 3, one edge of the blade is provided with a reinforcing strip 18 adapted to lie within the channel of the carrier and to prevent withdrawal of the blade 60 therefrom except by an endwise movement. As a means of locking the blade within the carrier, I have shown one of its sides 16 to be cut away as at 19 (see Fig. 5), its other side along the inturned edge 17 being provided with a lug or projection 20 adapted to spring to a position ahead of the blade when the latter is secured in place. In order to remove the blade from the carrier, it is merely necessary that the projection 20 be 70 sprung away from an interfering position ahead of the blade.

The walls of the carrier at its opposite end are suitably formed to co-operate with the ears 13 to hingedly connect with the handle, 75 a shoulder 21 being further provided to abut the shoulder 12 (see Fig. 1). In open position, as shown in this figure, the end of the carrier extends laterally of the handle to afford upper and lower abutments against 80 which the fingers may rest to maintain the parts against closing, thus obviating the necessity of a spring for this purpose. When the blade is closed within the handle, as indicated in Fig. 2, a projection 22 that 85 extends from the carrier is adapted to seat within the notch 11 of the eye 10, and may be unseated only by slightly spring the eye, thereby tending to retain the blade within the handle when the device is folded up. 90

The construction of this knife is exceedingly simple, and inexpensive. It permits of ordinary razor blades to be used, and to be replaced readily whenever desired. Such advantages, of course, are not attainable in 95 the usual knife constructions. Accordingly I desire that the principles of this invention, as exemplified in the preceding description or as may be otherwise embodied, be included within the scope of this patent, particularly as defined by the claims following:

I claim:

1. A knife having, in combination, a 105 handle formed of sheet metal that is bent to provide a channel with the edges thereof bent inwardly upon themselves but spaced apart from each other an appreciable distance, a carrier also formed of sheet metal that is bent to provide a channel with the 110

edges thereof bent towards each other but terminating apart from each other an appreciable distance, one of the sides of the carrier adjacent one end being cut away and the edge upon the other side of the carrier being provided with an element projecting toward said cutaway portion, a blade having its rear edge formed with an enlargement and adapted to slidably fit within the carrier, the turned edges of the carrier preventing movement of the blade therein excepting in a direction lengthwise of the blade, the element projecting from one side of the carrier being arranged to recede during sliding movements of the blade but to spring out beyond the proximate blade end when the blade is in final position, and a hinged connection between the handle and carrier adapted to provide a stop for the opposite end of the blade, the space between the bent edges of the handle being adapted to receive the blade when the carrier is

folded upon the handle, substantially as described.

2. A knife having, in combination, a handle of channel formation, a carrier hinged to the handle, and also of channel formation with its edges bent toward each other, a portion of one carrier side adjacent one end being cut away, and an element being projected toward said cutaway portion from the edge upon the opposite side of the carrier, and a blade provided on its rear edge with an enlargement and adapted to slidably fit within the carrier, the projecting element acting to spring ahead of the blade when the latter is in final position within the carrier so as to normally prevent dislocation of the same, substantially as described.

EDWARD C. DELSING.
